HANDLE FOR A BRIEF CASE OR SIMILAR ARTICLE

Harold Schneider, New Bedford, Mass.

Application May 10, 1950, Serial No. 9,852

Term of patent 14 years

(Cl. D87—2)

To all whom it may concern:

Be it known that I, Harold Schneider, a citizen of the United States, residing at New Bedford, in the county of Bristol and State of Massachusetts, have invented a new, original, and ornamental Design for a Handle for a Brief Case or Similar Article, of which the following is a specification, reference being had to the accompanying drawing, forming part thereof.

In the drawing:

Fig. 1 is a front elevational view of a handle for a brief case or similar article showing my new design;

Fig. 2 is a vertical sectional view taken on the line 2—2 of Fig. 1;

Fig. 3 is a top plan view of Fig. 1;

Fig. 4 is a horizontal sectional view taken on the line 4—4 of Fig. 1; and

Fig. 5 is a rear elevational view of Fig. 1.

I claim:

The ornamental design for a handle for a brief case or similar article, as shown,

HAROLD SCHNEIDER.
